DESIGN FOR A FISH LURE

Alexander Sisco, Bronson, Mich., assignor to Shurebite Inc., Bronson, Mich., a corporation of Michigan

Application May 31, 1946, Serial No. 130,298

Term of patent 14 years

(Cl. D31—4)

To all whom it may concern:

Be it known that I, Alexander Sisco, a citizen of the United States, and a resident of Bronson, in the county of Branch and State of Michigan,
have invented a new, original, and ornamental Design for a Fish Lure, of which the following is a specification, reference being had to the accompanying drawing, forming part thereof.

Figure 1 is a top plan view of a fish lure, showing my new design;

Figure 2 is a side view of the fish lure, illustrated in Figure 1; and

Figure 3 is a bottom view of the fish lure.

I claim:

The ornamental design for a fish lure, as shown.

ALEXANDER SISCO.
